UNITED STATES PATENT OFFICE.

JOHN E. HUBBELL, OF NEW YORK, N. Y., ASSIGNOR, BY DIRECT AND MESNE ASSIGNMENTS, OF ONE-THIRD TO LOUIS WILPUTTE AND TWO-THIRDS TO ALICE A. WILPUTTE, BOTH OF NEW ROCHELLE, NEW YORK.

REGENERATIVE COKE OVEN.

1,402,770.

Specification of Letters Patent. Patented Jan. 10, 1922.

Application filed December 27, 1918, Serial No. 268,479. Renewed May 11, 1921. Serial No. 468,727.

To all whom it may concern:

Be it known that I, JOHN E. HUBBELL, a citizen of the United States, and resident of New York, in the county of New York and State of New York, have invented certain new and useful Improvements in Regenerative Coke Ovens, of which the following is a specification.

My present invention relates primarily to regenerative coke ovens of the Wilputte type, examples of which are illustrated in Patent No. 1212866, granted January 16, 1917, to Louis Wilputte.

In this type of coke oven the heating walls at the sides of the horizontal coking chambers of the battery are each provided with a plurality of vertical flues which are connected at their upper ends by a horizontal channel, and are connected at their lower ends to a corresponding plurality of regenerators. In practice the regenerators connected to the flues of each heating wall are arranged in a row running lengthwise of the heating wall and located below the level of the latter, there being an individual connection between each regenerator and the corresponding vertical flue. There may thus be an individual regenerator cell for each vertical heating flue in the oven battery, or the regenerators may extend longitudinally of the oven battery; that is, transversely to the lengths of the heating chambers and coking chambers, in which case each of these longitudinal regenerators is connected to a corresponding vertical flue in each of the various heating walls.

The general object of my invention is to provide improved means for regulating the distribution of gaseous fluids flowing through the regenerators and heating flues to which the latter are connected. One specific object of the present invention is to provide an improved arrangement of conduit connections to the bottom sides of the regenerators, facilitating the maintenance of the pressure conditions in the different regenerators necessary to the desired distribution of flow through. This improved arrangement comprises conduit connections for regenerators adjacent the center of the battery, which are different from the conduit connections for the regenerators adjacent the outer sides of

the batteries. With this arrangement I am able to compensate in a very satisfactory manner for the tendency, resulting from variations in static and dynamic pressure conditions in the upper horizontal channel and in the bottom conduits, to concentrate the upflow in the "on" regenerators nearest the center of the battery, and to concentrate the downflow in the "off" regenerators at outer side of the battery. This arrangement also permits of a ready adjustment of the relative pressures maintained in the inner and outer regenerators to meet varying conditions of operation.

A second specific object of the invention is to equalize the pressure condition along the lengths of regenerators in a Wilputte oven having longitudinal regenerators. This object I attain by providing each of the longitudinal regenerators with an individual unobstructed sole channel. Associated with these sole channels are outlet conduits which are parallel to the oven chambers and heating walls, and extend into the battery from its opposite sides. Each of the regenerator sole channels is connected at distributed points along its length to a number of these conduits. The sole channels are of ample cross section to permit such flow longitudinally of the regenerator as is required to affect a proper distribution of the gaseous fluids flowing through each of the regenerators. Special constructions which I have devised for accomplishing the second mentioned specific object of my invention serve also to accomplish the first mentioned specific object of my invention in a desirable manner.

The various features of novelty characterizing my invention are pointed out with particularity in the claims annexed to and forming a part of this specification. For a better understanding of my invention, however, the advantages possessed by it, and various special objects attained by its use, reference should be made to the accompanying drawings and descriptive matter, in which I have illustrated and described preferred embodiments of my invention.

Of the drawings:

Fig. 1 is a sectional elevation of a coke oven, the right hand portion being in sec-

tion on the broken line 1—1^A of Fig. 3, the major part of the left hand portion of the figure being in section on the broken line 1—1^B of Fig. 3, and the lower left hand corner of the figure being in section on the broken line 1^C to 1^C of Fig. 3.

Fig. 2 is a view taken similarly to the right hand portion of Fig. 1, but on a larger scale and showing a small portion of regenerator 10 construction and the external connections thereto.

Fig. 3 is a section, the right hand portion of which is taken on the line 3—3 of Fig. 1, while the left hand portion is taken on the 15 line 3^A—3^A of Fig. 1.

Fig. 4 is a partial plan in section on the line 4—4 of Fig. 1.

Fig. 5 is a partial section taken similarly to Fig. 3, but on a larger scale and illustrating a modification.

Fig. 6 is a partial section taken similarly to Fig. 5, showing a second modification.

Fig. 7 is a partial section taken similarly to Fig. 5, showing a third modification.

Fig. 8 is a view taken similarly to Fig. 5, showing a fourth modification.

Fig. 9 is a partial plan in section on line 9—9 of Fig. 8.

Fig. 10 is a partial section taken similarly 30 to Fig. 5, illustrating the application of one feature of my invention of a Wilputte oven having individual cell regenerators for the different heating flues.

In the drawings, and referring first to the 35 construction shown in Figs. 1—4 inclusive, wherein I have illustrated the application of my invention to a Wilputte coke oven having longitudinal regenerators. As shown in these figures, the oven comprises, horizontal coking chambers A, alternating with heating walls A', provided with vertical heating flues, the various vertical flues in each heating wall being connected by the usual upper horizontal channel C. It will be understood that in ordinary practice there 40 are usually forty or more coking chambers in each battery. The various vertical flues in each heating wall may be, and are shown as identical in construction, but for convenience are designated in groups by the reference symbols B, B', b, b'. As shown each of 45 these flue groups comprises approximately, but not exactly, one fourth of all the vertical flues in each heating wall. The different vertical flues in each heating wall are connected each by a corresponding port D to a corresponding longitudinal regenerator E beneath the flue. As shown, each longitudinal regenerator chamber comprises portions 50 formed by openings A³ in the so called "pillar" walls A² beneath the heating walls A', and communicating portions between the pillar walls and bounded at their sides by walls A⁴ extending transversely to the 55 pillar walls A². At one end of the battery

each regenerator space comprises also a portion A³⁰ in the battery end wall which is similar in shape to the pillar wall openings A³.

The checker brick E in each longitudinal 70 regenerator is so piled, and the bottom wall of the regenerating chamber is so formed as to provide an open sole channel E¹ extending the full length of the battery. Above the sole channel E¹ the checker brick in each 75 regenerator is piled to form a continuous pervious mass extending from one end of the battery to the other. In some of the figures of the drawings, for convenience, only a portion of the checkerbrick is shown. 80 Advantageously each sole channel E¹ is of the same width as the pillar wall openings A³ except that, for constructional reasons, each channel E¹ is shown as slightly restricted in its pillar wall opening portions 85 by the inclination of the side walls of the latter as indicated at A⁵ to provide supporting ledges for the bottom row of checker-bricks stacked in the pillar wall openings. Extending into the battery structure from 90 its opposite sides are waste heat outlet conduits G, G', g and g'. The conduits G, which extend into the battery at the left hand side, as seen in Fig. 4, for approximately one quarter of the width of the battery, are connected to the sole channels E¹ of the regenerators, which are connected at 95 their upper ends to the flues B. All of the conduits G, except the right hand one as seen in Fig. 3, are connected to the corresponding sole channels E¹ by inclined ports H, which open at their lower ends at the sides of the conduits G and open at their upper ends to the sole channel E¹ centrally of the 100 openings A³ in alternate pillar walls A². 105

For structural convenience, the conduit G at the right hand end battery, as seen in Fig. 3, is connected to the sole channels E¹ above it, by vertical ports A¹⁰ through the top wall of the conduit. The conduits G¹, 110 which alternate with the conduits G and enter the battery from the same side, extend to the center of the battery and are connected by ports H¹ similar to ports H, to the sole channels E¹ of the regenerators 115 having their upper ends connected to the flues B'. The ports H¹ are similar in shape to the ports H and open at their upper ends into the pillar wall openings A³⁰ and A³ in rows of said openings alternating with the 120 rows of such openings into which the ports H open. The channels g which are in line with the channels G' and extend into the battery from its right hand side as seen in Fig. 4 are connected by ports h to the sole 125 channels E¹ of the regenerators connected at their upper ends to the flues b. The conduits g' which alternate with the conduits g are connected by ports h' to the sole channels E¹ of the regenerators E connected 130

to the flues b' . The ports h and h' are shown as similar in form to the ports H and H' .

The flow capacity of the ports H , H' , etc., connecting the conduits H , H' , h and h' to the corresponding regenerator sole channels should be carefully proportioned to secure the proper flow restricting and regulating effect. In practice I prefer to accomplish this by use of orifice plates J which may advantageously be formed of cast iron, one of these plates J being received in a recess formed in the bottom wall of the corresponding channel E^1 at the upper end of each of the ports H , H' etc. Each orifice member J has an orifice of measured diameter, and smaller in cross section than the brick work portion of the port of which it forms a part.

Extending into the coke oven battery from its opposite sides are brick work channels I . These channels, which are located below the regenerator and run to the center of the battery, are arranged in end to end pairs, one of which lies between each two adjacent pillar walls. Each channel I is connected to the sole channels E^1 of the regenerators above it by a brick work port I^2 and receives a metallic pipe I^1 , having carefully proportioned discharge orifices, which register with the corresponding ports I^2 .

In the construction shown, tunnels M and m are provided at the opposite sides of the battery. These tunnels communicate at one end of the battery through a common stack channel Mm with a chimney or other draft producing device (not shown).

Valves O and O' are provided to open and close communication between the channels M and m , respectively, and the stack outlet Mm . The tunnel M is connected at the end of the battery by a branch P , to the outlet Pp of a blower or other source of air under pressure. Similarly the tunnel m is connected to the air source Pp by a branch tunnel p . The flow through the branch tunnels P and p is controlled by valves Q and Q' respectively. The outer end of each of the conduits G and G' is connected by a corresponding valve K to the tunnel M , and each of the conduits g and g' is connected by a similar valve K to the tunnel m . Each valve K comprises a valve member K^1 controlling communication between the corresponding waste heat conduit and the corresponding tunnel M or m , and as shown, each valve member K^1 is provided with an extension K^{10} controlling a port K^2 through which the tunnel is connected to an air pipe I' adjacent the valve, the arrangement being such that each of the tunnels M and m is alternately connected to the corresponding air pipes I^1 and to the corresponding waste heat channels G and G' or g and g' .

The valve members K' and the valves O , O' , Q and Q' are connected to suitable re-

versing mechanisms, not shown, and valves (not shown and also connected to a reversing mechanism) are provided for controlling the supply of combustible gas to the usual "gas guns" or channels R . The channels R , are connected to the various vertical flues B , B' , b and b' by ports R' and the usual removable gas nozzles R^2 .

In operation, and assuming the stage of operation in which combustion is being initiated in the flues b and b' , the valve members K^1 of the valves K at the right hand side of the battery, as seen in Fig. 4 will be closed, and the valve members K^1 of valve K at the left hand side of the figure will be open. At the same time the valves O and Q' will be open, and the valves O' and Q will be closed. Air then passes from the air supply source P , p , through the branch p and tunnel m to the valves K at the right hand side of the battery and through the then open ports K^2 of those valves into the air pipes I supplying air to the sole channels E^1 of the regenerators E connected to the flue b and b' ; at the time combustible gas is supplied to the flues b and b' through the corresponding ports R^1 .

The air and gas uniting in combustion in the flues b and b' of each heating wall, pass out of the latter into the upper horizontal channel C through which the products of combustion pass to the upper end of the corresponding flues B and B' . After descending through the flues B and B' , the products of combustion enter the upper ends of the corresponding regenerators E through the ports D , and after passing through the checkerbrick of the regenerators under the flues B and B' , and thereby being cooled while heating the regenerators up, pass into the sole channels E^1 of those regenerators. From the sole channels E of these then "off" regenerators, the products of combustion pass through the ports, H , H' and H^{10} to the conduits G and G' and thence through the corresponding valves K to the tunnel M and through the latter to the stack outlet Mm . In the following stage of operation, the valves are shifted to reverse the flow, combustion then being initiated at the bottoms of the flues B and b , and the products of combustion then escaping from the oven structure proper through the channels g and g' and tunnel m .

The provision of separate outlet conduits G and G' or g and g' for the outer and inner portions of each set of regenerators in which the direction of flow at any instant is the same, gives a capacity for regulation which is practically advantageous, and from a practical standpoint, has not heretofore been obtainable.

This capacity for regulation results from the ability to vary the draft suction applied to the outer regenerators as compared to that

applied to the inner regenerators. This variation in suction effect may be obtained by a mere adjustment of the usual dampers K^3 provided in the casings of the corresponding valves K . By thus varying the suction applied to different regenerators it is possible to substantially compensate for the disturbing effects on distribution of the static and dynamic pressure conditions prevailing in the upper horizontal channel C , and in the waste heat conduits G , G' and g , g' . In the upper horizontal channel C , for instance, the total pressure is the same from one end of the channel to the other, but this total pressure comprises static and dynamic components which vary inversely. At the ends of the channel the dynamic pressure component is zero, while at the center of the channel, that is, at the point midway between the inner flue b and b' the dynamic pressure component is a maximum. The static component, disregarding friction losses, varies from the same maximum at each end of the channel to a minimum at the center of the channel. Similarly in the waste heat conduits G and G' , etc., the dynamic pressure increases and the static pressure diminishes with the increased volume of flow from the inner to the outer end of the portion of each conduit into which there is a distributed inflow. The controlling pressures determining the volume of flow downward through any vertical flue B , B' and b or b' are the static pressure in the channel C at the top of the flue, and the static pressure in the regenerator to which the lower end of the flue is connected, and the regenerator pressure depends in turn upon the static pressure at the outlet ports leading from the sole channel E' of the regenerator into the waste heat conduits to which it is connected by those ports. In consequence of the described static pressure variations in the horizontal channels C and off-take conduits there is a tendency to concentrate the downflow in the vertical flues at the outer sides of the battery as compared with the vertical flues adjacent the center of the battery. This tendency can be substantially minimized with ease in the apparatus described, by so setting the dampers that the draft suction in the conduits G' and g' is greater than it is in the conduits G and g . The regulation thus obtained may be supplemented, if it is found necessary or desirable, by a graduation of the size of the orifices in the various orifice members J , opening to each of the corresponding conduits G , G' , g and g' . Theoretically, the greater the number of flue groups, each with its separate offtake conduits, the better, but I believe practically satisfactory results are obtainable with the simple arrangement shown in which there are but two sets of such connections

for each set of regenerators through which the flow at any one instant is in the same direction. With the two sets of connections shown, it is possible to pass down through each of the groups of flues B , B' , b or b' the exact portion of the downflowing gases which should pass through that group of flues. Furthermore, those skilled in the art will understand that an error of a given magnitude in proportioning the orifice members J for the group of regenerators connected to the outlet conduits G , for instance, to meet a given operating condition, will result in a maximum fault in distribution which is but a fraction (approximately one-fourth) of the fault which a corresponding error in proportioning orifices would create if the regenerators connected to the flues B' were also connected to the conduit G .

The proper distribution of the up-flow through the regenerators and vertical heating flues is no less important than the regulation of down flow, and separate air supply conduits for different groups of regenerators may be provided as shown in Figs. 8 and 9 hereinafter referred to in more detail. Such a multiplication of air supply pipes will ordinarily be found unnecessary, I believe, because of the comparative ease with which the pipes I' may be withdrawn and their discharge orifices enlarged by reaming or be partially plugged if the necessity for such adjustment arises. Moreover, changes in operating conditions do not materially alter the temperature conditions in the air supply pipes I' as they may in the waste heat channels. In the drawings I have shown the usual slide bricks C' at the upper ends of the vertical flues which may readily be used if considered necessary or desirable though I believe them to be unnecessary in a well designed oven having the other regulating provisions disclosed herein. Removable and replaceable throttling devices C^2 which may be, and are shown in Fig. 1 as consisting of bricks or like refractory blocks, may be placed in each horizontal channel C at the flow reversal plane to form means by which the relative volumes of flow in the different heating walls may be varied. The provision of an unobstructed sole channel through the pillar wall openings A^3 of each longitudinal regenerator and the connection of the underlying conduits to the regenerators by ports opening from the centers of the pillar wall openings each tends to create a more active flow through the checker brick in the pillar wall openings and hence to increase the regenerating effectiveness of the latter. The provision of the ports opening centrally from the bottoms of the pillar wall openings also facilitates an arrangement of ports which are

similar in shape and length and hence tend to equalize the flow through the various ports of each regenerator. The modified construction shown in Fig. 5 differs from 5 that shown in Figs. 1-4 only in the shape of the ports HA connecting the regenerator sole channels to the waste heat conduits. As shown in Fig. 5, each port HA is elbow shaped, comprising a horizontal branch 10 leading from the side of the waste heat channel, in which may be placed a regulating orifice member JB, which may be removed and replaced by one of a different size if necessary.

15 In the modification shown in Figs. 6 and 7 the longitudinal regenerator sole channels E¹⁰ are formed in the masonry below the air supply channels I and the waste heat channels G¹⁰ and G¹¹. It will be understood that in the construction shown in 20 Fig. 6 the channels G¹⁰ and G¹¹ correspond in length to channels G and G' respectively; the channels G¹⁰ being connected by ports G¹² to the sole channels E¹⁰ of the regenerators adjacent the outer sides of the battery, while the channels G¹¹ are connected by ports G¹³ to the sole channels E¹⁰ of the 25 inner regenerators. Each sole channel E¹⁰ is connected to the regenerator chamber 30 above it by vertical channels H¹⁰ leading downward from the centers of the pillar wall portions A⁸ of the regenerators. With the arrangement shown in Fig. 6 it is possible to provide removable orifice members, 35 JA, or slide bricks for regulating the flow through the ports G¹² and G¹³.

In the construction shown in Fig. 7, there 40 is one short waste heat channel, G¹⁵ and one long waste heat channel G¹⁶ for each four heating walls. In Fig. 7, ports H¹⁵ in the top wall of each sole channel E¹⁰ are connected by bifurcations H¹⁶ to the central portion of each of the pillar wall openings A⁸ above the sole channel. With this 45 arrangement, as with that shown in Figs. 1-6, the paths of flow from the portions of the regenerator space at the opposite ends of each pillar wall opening A⁸ to the nearest waste heat channel, are similar in shape 50 and in length. In Fig. 7, the discharge ports from the air supply channel I open into the vertical upper portions H¹⁶ of the passages leading to the waste heating channel.

55 In the arrangement shown in Figs. 8 and 9, the ports leading to the long and short waste heat channels at opposite sides of a pillar wall open into the lower end of the openings A⁸ in that pillar wall. This 60 arrangement of waste heat channels slightly simplifies the brick work, as compared with the arrangement shown in Fig. 8, from which it need not differ except in so far as the arrangement of waste heat channels is 65 concerned. The construction shown in Fig.

8 is usable without special construction of waste heat channels at the ends of the battery in case there is an odd number of coking chambers and an even number of heating chambers in the battery.

In Fig. 8 the air pipe channels other than the two channels at the opposite ends of the battery are divided into separate channels for inner and outer groups of regenerators just as are the waste heat channels. As 75 shown the intermediate air supply channels IA are connected to the regenerator sole channels E¹ by bent ports, I²⁰, opening to the air channels at the sides and opening to the regenerator sole channels at the bottoms of the openings A⁸ in the pillar walls intermediate of the pillar walls into which the offtake ports H etc. open. At the ends of the battery the air pipe channels run to the center of the battery and are each connected 80 to all of the regenerator sole channels above it.

In Fig. 10 I have illustrated the application of the divided waste heat channel feature of my invention to a Wilputte oven of 90 the type in which there is an individual cell regenerator EA for each vertical flue. In this arrangement there are beneath each row of cell regenerators extending transversely of the battery a pair of waste heat 95 channels G⁴⁰ and a pair of waste heat channels G⁵⁰. The two channels G⁴⁰ of each pair extend into the battery from its opposite sides and each of these channels is connected to approximately one quarter of the regenerators by ports G⁴¹. The two channels G⁵⁰ underneath each row of regenerators also extend into the battery from its opposite sides and run to the flow reversal plane and are connected by ports G⁵¹ to the intermediate 100 regenerators. An aligned pair of supply channels IB is interposed between the channels G⁴⁰ and G⁵⁰ underneath each row of regenerators, each air supply channel running from the outer edge of the battery to 110 the flow reversal plane and being connected to the regenerators above it by ports I².

While in accordance with the provision of the statutes I have illustrated and described the best embodiments of my invention now known to me, those skilled in the art will understand that changes may be made in the form of my invention without departing from the spirit of my invention as set forth in the appended claims, and that 115 certain features of my invention may sometimes be used to advantage without a corresponding use of other features.

Having now described my invention, what I claim as new and desire to secure by Let. 125 ters Patent, is:

1. In a coke oven having a heating wall formed with a plurality of vertical heating flues connected at their upper ends, and having a plurality of regenerators separately 130

- connected to the lower ends of said flues and forming two sets, one at each side of a central flow reversal plane and with the regenerators in each set all "on" or all "off" 5 at the same time, the improvement which consists in separate conduit connections for groups of regenerators of each set located at different distances from said flow reversal plane.
- 10 2. In a coke oven having a heating wall formed with a plurality of vertical heating flues connected at their upper ends, and having a plurality of regenerators separately connected to the lower ends of said flues and 15 forming two sets, one at each side of a central flow reversal plane and with the regenerators in each set all "on" or "off" at the same time, the improvement which consists in separate "off gas" outlet conduits for 20 groups of regenerators in each set located at different distances from said flow reversal plane.
- 10 3. In a coke oven battery comprising a plurality of horizontal coking chambers and intervening heating walls extending transversely of the battery with each of said heating walls formed with a plurality of vertical heating flues connected at their upper ends, a plurality of regenerators extending longitudinally of the battery and corresponding 25 in number to the number of flues in each heating wall and each separately connected to a corresponding flue in each of the heating walls and forming two sets, one at each 30 side of a central flow reversal plane and with the regenerators in each set all "on" or "off" at the same time, the improvement which consists in conduit connections to the bottom of the regenerators, said connections extending 35 transversely of the battery and being separately connected to groups of regenerators of each set located at different distances 40 from said flow reversal plane.
- 10 4. In a coke oven battery comprising a plurality of horizontal coking chambers and intervening heating walls extending transversely of the battery, with each of said heating walls formed with a plurality of vertical heating flues connected at their upper ends, a plurality of regenerators extending 45 longitudinally of the battery and corresponding in number to the number of flues in each heating wall, and each separately connected to a corresponding flue in each of 50 the heating walls, the improvement which consists in a separate unobstructed sole channel for each regenerator extending longitudinally of the battery.
- 10 5. In a coke oven battery comprising a plurality of horizontal coking chambers and intervening heating walls extending transversely of the battery, with each of said heating walls formed with a plurality of vertical heating flues connected at their upper ends, a plurality of regenerators extend- 55
- ing longitudinally of the battery and corresponding in number to the number of flues in each heating wall and each separately connected to a corresponding flue in each of the heating walls, the improvement which 60 consists in a separate unobstructed sole channel for each regenerator extending longitudinally of the battery, and conduits extending transversely of the battery and connected to the regenerator sole channels at intervals along the lengths of the latter. 70
6. A coke oven battery having horizontal coking chambers and intervening heating walls and subjacent pillar walls all extending transversely of the battery, said pillar walls being formed with openings and being connected by partition walls, transverse to the pillar walls to provide a plurality of regenerator chambers extending longitudinally of the battery and containing checker brick, 80 with said chambers so shaped and the checker brick so disposed therein as to provide an unobstructed sole channel for and extending through the pillar wall openings of each of said longitudinal regenerator chambers. 90
7. A coke oven battery having horizontal coking chambers and intervening heating walls and subjacent pillar walls all extending transversely of the battery, said pillar walls being formed with openings and being connected by partition walls transverse to the pillar walls to provide a plurality of regenerator chambers extending longitudinally of the battery and containing checker brick, 85 with said chambers so shaped and the checker brick so disposed therein as to provide an unobstructed sole channel for and extending through the pillar wall openings of each of said longitudinal regenerator chambers, and conduit connections to said sole channels extending transversely of the battery and connected to said sole channels by ports leading downward from the latter through the floors of the pillar wall openings. 95
8. A coke oven battery having horizontal coking chambers and intervening heating walls and subjacent pillar walls all extending transversely of the battery, said pillar walls being formed with openings and being connected by partition walls transverse to the pillar walls to provide a plurality of regenerator chambers extending longitudinally of the battery, conduits located beneath the regenerator chambers and connected to said chambers by ports leading downward through the floors of the pillar wall openings. 100
9. A coke oven battery having horizontal coking chambers and intervening heating walls and subjacent pillar walls all extending transversely of the battery, said pillar walls being formed with openings and being connected by partition walls transverse to the pillar walls to provide a plurality of 110
- 115
- 120
- 125
- 130

regenerator chambers extending longitudinally of the battery, conduits located beneath the regenerator chambers and extending transversely of the battery between the 5 pillar walls, and connected to said chambers by ports leading downward through the floors of the pillar wall openings.

10. A coke oven battery having horizontal coking chambers and intervening heating 10 walls and subjacent pillar walls all extending transversely of the battery, said pillar walls being formed with openings and being connected by partition walls transverse to the pillar wall openings to provide a plurality of regenerator chambers, extending longitudinally of the battery, conduits located beneath the regenerator chambers and extending transversely of the battery between the pillar walls and connected to said 15 chambers by ports leading downward through the floors of the pillar wall openings, one conduit of each adjacent pair of said conduits being connected to a group of regenerators adjacent the outer face of the 20 battery, and the other to a group of regenerators adjacent the center of the battery.

11. In a coke oven battery comprising a plurality of horizontal coking chambers, and 30 intervening heating walls extending transversely of the battery, with each of said heating walls formed with a plurality of vertical heating flues and an upper horizontal channel to which the upper ends of 35 the vertical flues are connected a plurality of regenerators extending longitudinally of the battery and corresponding in number to the number of flues in each heating wall and each separately connected to a corresponding 40 flue in each of the heating walls, and forming two sets one at each side of a central flow reversal plane with the regenerators in each set all "off" or all "on" at the same time the improvement which consists 45 in means for separately throttling the various horizontal channels each adjacent the flow reversal plane.

12. In a coke oven having a series of hori-

zontal coking chambers and a series of heating walls alternating with the coking chambers and each formed with a plurality of vertical heating flues connected at their upper ends and supporting walls beneath and parallel to the heating walls and walls transverse to the supporting walls dividing the 50 space between each pair of supporting walls into a plurality of regenerator chambers separately connected to the lower ends of the flues in an adjacent heating wall and forming two sets one at each side of a central flow reversal plane with the regenerators in each set all "on" or all "off" at the same time, the improvement which consists in separate conduit connections for groups of regenerators of each set located at different distances from said flow reversal plane. 55

13. In a coke oven having a series of horizontal coking chambers and a series of heating walls alternating with the coking chambers and each formed with a plurality of vertical heating flues connected at their upper ends and supporting walls beneath and parallel to the heating walls and walls transverse to the supporting walls dividing the 60 space between each pair of supporting walls into a plurality of regenerating chambers separately connected to the lower ends of the flues in an adjacent heating wall and forming two sets one at each side of a central flow reversal plane with the regenerators in each set all "on" or all "off" at the same time, the improvement which consists in separate conduit connections for groups of regenerators of each set located at different distances from said flow reversal plane, 65 said conduit connections being parallel to and extending between said supporting walls. 70

Signed at New York city, in the county of 90 New York and State of New York this 26th day of December, A. D. 1918.

JOHN E. HUBBELL.
